CLAIM

The ornamental design for a wire spoke basket for wheels, as shown and described.

DESCRIPTION

FIG. 1 is a front elevational view of a wire spoke basket for wheels showing our new design;

FIG. 2 is a rear elevational thereof;

FIG. 3 is a side elevational view thereof;

FIG. 4 is a cross sectional view taken along line 4—4 of FIG. 1;

FIG. 5 is a front elevational view of a wire spoke basket for wheels showing a second embodiment of our new design;

FIG. 6 is a side elevational view of the FIG. 5 embodiment;

FIG. 7 is a rear elevational view of the FIG. 5 embodiment;

FIG. 8 is a side elevational view of the FIG. 5 embodiment.

The broken lines shown in FIGS. 3, 4 and 8 are for illustrated purposes only.

FIG. 3.

FIG. 1

FIG. 4.

FIG. 2.

FIG. 5.

FIG. 6.

FIG. 7.

FIG. 8.
